CLAIM

The ornamental design for a vehicle roof rack clamper, as shown and described.

DESCRIPTION

FIG. 1 is a perspective view of a “vehicle roof rack clamper” showing my design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a use schematics view of a vehicle roof rack clamper; and,

FIG. 9 is another use schematics view of two vehicle roof rack clamps.

In the drawings, the broken lines in FIGS. 8 and 9 depict portions of a vehicle and form no part of the claimed design.
